THERMOSTAT.

Specification of Letters Patent. Patented Mar. 20, 1917.

Application filed June 10, 1914. Serial No. 844,355.

To all whom it may concern:

Be it known that I, WALTER H. KALLENBACH, a citizen of the United States, residing at Boston, in the county of Suffolk and State of Massachusetts, have invented a new and useful Improvement in Thermostats, of which the following is a specification, reference being had therein to the accompanying drawings.

10 This invention relates to thermostats of that class commonly used to actuate a fire alarm system in which an expansion member is operated to close an electric circuit to operate the alarm when the temperature in the room or space where the thermostat is located is raised to a predetermined degree.

20 The main object of the invention is to provide a thermostat of the above described class which is of cheap and durable construction and which is sure, efficient and positive in its operation.

25 Another object of the invention is to provide a thermostat having two expansion members, without increasing the size of the thermostat, thereby making its operation doubly certain.

30 A further object of the invention is to provide expansion members of such form that when they are caused to expand by the rising of the temperature in the room, the circuit is closed by a sliding contact so that any dust, dirt or corrosion which accumulates at the point of contact will be removed by the glancing or sliding movement of the expansion member thereby assuring a free 35 passage for the electric current.

40 Another object of the invention is to provide an expansion member having a wide range of movement when expanded by heat in order to make the device sensitive and to allow the air gaps between the expansion members and the terminals to be so wide that a collection of moisture on the expansion member and terminals will not result in a short circuiting of the current.

45 Another object of the invention is to provide a thermostat having its terminal plates entirely surrounded by a molded insulating material in order that short circuiting, due to the accumulation of moisture, may be effectively guarded against.

50 Other objects of the invention will be more specifically set forth and described hereinafter.

In the accompanying drawings illustrat-

ing the preferred form of my invention, Figure 1 is a plan view of a thermostat constructed in accordance therewith; Fig. 2 is a central vertical sectional view on line 2—2 in Fig. 1; Fig. 3 is a central vertical sectional view on line 3—3 in Fig. 1; Fig. 4 is a view in perspective of a terminal plate and Fig. 5 is a side elevation of said terminal plate.

65

In the illustrated embodiment of my invention is shown a thermostat comprising a base 6 provided with two terminal plates 8 each having an expansion member 10 adapted to engage the other terminal plate to close an alarm circuit when the temperature rises to a predetermined degree.

The base 6 is composed of non-conducting material such for instance as vulcanized rubber and the terminal plates 8 are embedded therein with the exception of certain portions which project therefrom. Each terminal plate 8 consists of a body portion having a lateral portion 12 extending obliquely therefrom and lying in the same plane. The inner end of the body portion and the end of the lateral extension are turned upwardly to form posts 14 and 16 respectively. The outer end of the body portion is provided with a hole 18 to receive a screw 20 for the purpose of securing thereto one wire of the electric circuit in which the thermostat is arranged. When the terminal plates are embedded in the base the only portions which project are the ends to which the circuit wires are attached and the posts 14 and 16. The remaining portions of the terminal plates are entirely surrounded by and inclosed in the base, that is, in a non-conducting material.

75

90 In making the base I prefer to use a non-conducting material which can be molded around the terminal plates in the desired form while in a plastic condition and compressed and then hardened either by vulcanization or in any other way. Constructing the base in this manner reduces the cost of manufacture and secures efficiency by insulating all the parts of the terminal plates except those portions which are attached to the circuit wires, contact members and expansion members.

95

100 To the post 14 of each terminal plate is secured by a screw 22 an expansion member 10 which may be made of any suitable material or of two metals having different coefficients of expansion. Each of these mem-

105

bers consists of two U-shaped portions in a substantially perpendicular relation to each other (see Fig. 1) and this form of the expansion members constitutes the most important feature of my invention, and its advantages will be pointed out hereinafter.

In the post 16 of each plate is arranged a screw 24 which operates as a contact member for the expansion member upon the other plate and by turning the screws the air gaps between the expansion members and the contact members may be increased or diminished and the temperature at which the thermostat will operate to sound an alarm thereby regulated.

The arrangement of the expansion and contact members is illustrated in place in Fig. 1, the terminal plates being shown in dotted outlines, the end 26 of each expansion member engaging the contact screw 24 and thereby closing the circuit between the two terminal plates.

For the purpose of securing the thermostat in place on the ceiling or wall of a room, the base is provided with a central boss or hub 28 having a hole 30 to receive a nail or screw and this hub is preferably formed of the same non-conducting material as the base. Any other suitable means may, however, be employed for securing the device in place. The base of the thermostat, it will be noticed, is convex which prevents the accumulation of moisture thereon and any short circuiting at that point.

A cover 32 may be provided for inclosing the operative parts and is preferably pierced by holes 34 to permit the air to have free circulation through the cover and in contact with the expansion members.

When in use a thermostat is arranged in an electric circuit the wires 36 and 38 of the circuit being connected one to each terminal plate 8 by means of the screws 20. In this connection it will be observed that the ends 40 of the terminal plates are turned upwardly as shown in Fig. 2 which is downwardly when the thermostat is secured to a ceiling and the circuit wires 36 and 38 are held in the angles thereby formed by the screws 20. This construction has several advantages in that the circuit wires are not cut by the heads of the screws when they are turned down too hard and if the thermostat becomes detached from the ceiling by reason of vibration or otherwise, it is supported by the circuit wires and remains operative. The circuit is normally open and remains open until one or both of the expansion members engages the contact member or

members 24 when the circuit is closed and the current thereupon operates an alarm, sprinkler or other mechanism which is also in the circuit.

The operation of the device is as follows:

65 As the temperature in the room or space

where the thermostat is located goes up the expansion member is caused to expand and the end 26 approaches the contact member 24. If the thermostat be adjusted to 155 degrees then at that temperature the free end of the expansion member will engage the contact member and close the circuit which immediately actuates the alarm arranged within the electric circuit at some distant point.

As hereinbefore stated, the form of the expansion member or members is one of the most important features of my invention. I have found from a long series of experiments that this form of expansion member has several advantages. In the first place its form enables me to employ two expansion members and two contact members without increasing the size of the thermostat and when two sets of expansion and contact members are used, it constitutes what might be termed a double apparatus so that if for any reason one expansion member should fail to work, there is another to close the circuit and actuate the alarm. In the second place I secure an expansion member which is more sensitive and in which the arc traveled by the end of the expansion member as the temperature rises is greater than that of any other form of expansion member known to me. This enables the thermostat to be adjusted with a larger air gap between the contact member and the end of the expansion member so that short circuiting by reason of moisture accumulating either on the contact member or expansion member or both is rendered, for all practical purposes, impossible. This also enables the thermostat to be adjusted to a wider range of temperature and more accurately to any given temperature.

In the third place the expansion of the expansion member causes the end 26 to be moved in a direction perpendicular to the axis of the contact member so that after a contact is made between the contact member and the end of the expansion member, any further increase in temperature causes the end of the expansion member to slide upon the end of the contact member. This sliding contact will remove any dirt or corrosion which may have accumulated on the end of the expansion member and will ultimately make a good contact even if the first contact is inoperative.

It will be noticed in Fig. 1 of the drawings the expansion member, as it leaves the post 14, is bent slightly to one side. I have found by constructing it in this manner rather than having it lead from the post 14 practically in the same plane, results in a wider range of movement of the end 26 of the expansion member.

Although I have shown my thermostat as comprising two sets of expansion and con-

tact members in what may be termed a double construction, it may be used with but a single set if preferred. While the double set gives additional security so far as positive operation of the device is concerned, yet is not absolutely necessary to use two sets so far as the purposes of my invention are concerned.

My thermostat has the advantage of having comparatively few parts and of being extremely simple both in construction and operation so that it may be made at a very low cost. Owing to the construction of the base having terminals embedded therein, and in view of the wide gaps between the expansion and contact members, the gathering of moisture upon the thermostat cannot operate to cause a short circuiting and a premature sounding of the alarm.

It is to be understood that my invention may be embodied in other forms of construction than that herein shown and described and I desire to claim it broadly except where specifically limited in the following claims.
